HEATING DEVICE

Wunibald I. E. Kamm and Willy F. Krautter,
 Dayton, and Kurt Staiger, Wright-Patterson
 Air Force Base, Ohio

Application November 28, 1949, Serial No. 129,861

1 Claim. (Cl. 263—19)

(Granted under Title 35, U. S. Code (1952),
 sec. 266)

1

The invention described herein may be manufactured and used by or for the United States Government for governmental purposes without payment to us of any royalty thereon.

This invention relates to air heating devices generally more particularly to pulse jet space heaters of the air circulation type operating in acoustic resonance, having for an object the provision of a highly efficient heater, preferably of the liquid or gaseous fuel type, in which a maximum volume of air is heated, circulated, and delivered without the use of blowers, fans, or other auxiliary power operated devices.

A further object of our invention is the provision of a portable self-contained space heater that is light in weight, economical to manufacture, simple and easy to start, having means for efficiently heating, circulating and delivering large volumes of air solely by the use of a resonant air heating and combustion heater unit of the liquid or gaseous fuel type, utilizing high frequency oscillations of rapid intermittent explosions of the fuel mixture to supply the heat, circulate the air to be heated, and cause delivery of heated air in appreciable volumes to the place or area to be heated.

A further object is the provision of a space heater having a combustion chamber with a carburetor and fuel supply nozzle therefor including an elongated discharge pipe, employing the acoustic resonant or pulse jet motor operating principle and utilizing the pulse jet discharge to heat, circulate and effect delivery of large quantities of heated air from the heater, including means for reducing the back pressure effect on the carburetor fuel delivery nozzle for the combustion chamber following each explosion or pulse, incorporating fixedly associated means for securing a dryer and better vaporizing of the operating fuel mixture to produce an extremely efficient detonating effect in the pulse jet combustion cycle, particularly during the starting period, making it possible to initiate the pulse jet cycle into operation with ease and minimum delay under all weather and temperature conditions.

A further object is the provision of a space heater of the resonant pulse jet type, having an elongated combustion chamber formed with an improved air and fuel inlet check valve construction for introducing the explosive mixture into the combustion chamber for effecting more rapid movements of the check valves between their open and closed positions to thereby cause higher and faster pressure oscillations, improving the efficiency of the heater.

2

A further object is the provision of an improved pulse jet space heater utilizing the resonant pulse jet action and rapid pulse discharge from the combustion chamber for the heating, circulating and delivery of heated air in large volumes to a predetermined delivery point or space to be heated, incorporating heat exchange means for cooling the discharged products of combustion from the pulse jet structure and simultaneously heating and delivering an appreciable volume of fresh air therewith to a first delivery point inside of the heater in which aspirator means is provided adjacent the first delivery point for circulating, heating and mixing a second appreciable volume of air with the first volume of heated air and combustion products and effecting a rapid delivery of the same to a predetermined remote delivery point outside of the heater without the use of fans, blowers, or other independent power operated air circulating means.

A further object is the provision of an acoustically tuned resonant pulse jet type of air circulating heater which can be easily incorporated in aircraft power plant inclosing structures to maintain the aircraft engines and cooperating accessories at a desired temperature at all times, particularly when the engines are not in use to provide easier starting and also reducing the preliminary "warm-up" periods of the engines to a desired minimum.

A further object of our invention is the provision of an improved resonant pulse jet operated air heating structure having a portable cabinet including means for utilizing the radiant heat for regaining the vapor losses within the cabinet in which the cabinet comprises a light weight body or casing constructed to efficiently and effectively withstand excessive damage incident to hard usage while in storage, and during shipment and arranged for "nesting" by superimposing and interengaging any reasonable number of the cabinet heater units upon each other, whereby a battery of superimposed heaters may be utilized and put into simultaneous operation while nested to deliver great volumes of heated air at substantially any desired point or space that is to be heated.

A still further object is the provision of a resonant acoustically tuned pulse jet operated space heater incorporating an improved type of self-contained starting device for initiating the detonating action, including means for initially heating and introducing fuel and air into the combustion chamber under pressure in a dry and heated condition to effect a convenient and easy automatic starting of the space heater device,

even under low temperature and adverse weather conditions.

Other objects and advantages of the invention will become apparent from the following description, taken in connection with the accompanying drawings, in which like reference characters refer to like parts in the several figures.

Drawings

Fig. 1 is a side elevation of a space heater incorporating our invention;

Fig. 2 is an end elevation of the space heater shown in Fig. 1;

Fig. 3 is a transverse vertical sectional view of the space heater shown in Fig. 1, taken approximately on the plane indicated by line 3—3 in Fig. 2 looking in the direction of the arrows, parts of the apparatus being shown away or shown in elevation;

Fig. 4 is a vertical sectional view taken approximately on the plane indicated by lines 4—4 in Fig. 3, looking in the direction of the arrows;

Fig. 5 is an enlarged vertical fragmentary longitudinal sectional view taken through the supplemental fuel heating and supply means which supplies fuel and air to the pulse jet combustion chamber in a dry and heated state and heats the combustion chamber, primarily to start the resonant pulse jet action within the combustion chamber and tail pipe and illustrating the lower portion of the combustion chamber and valve chamber broken away and shown in section to illustrate the fuel and air inlet means, and the improved check valve arrangement;

Figs. 6 and 7 are enlarged detail views illustrating one of the forms of the combustion chamber check valve and seat arrangements that may be used, showing the same respectively in closed and open positions;

Figs. 8 and 9 are enlarged detail views of a modified form of check valve structure, including resilient actuators or spring means for accelerating the closing and opening actions of the check valve members following the detonation of the fuel mixture within the combustion chamber and discharge therefrom;

Fig. 10 is a somewhat diagrammatic view, illustrating a modified arrangement for supplying heated air to an aircraft engine and accessories mounted within a nacelle, in which the heated air supply conduits form a permanent structure within the nacelle, the improved heating apparatus being in the form of a compact individual detachable unit, capable of being applied to the aircraft structure for supplying heated air in appreciable volumes to the conduits; and

Fig. 11 is a plan view of the structure shown in Figs. 8 and 9.

Referring more particularly to Figs. 1 to 4 the reference numeral 1 denotes a rectangular or parallelepiped casing, formed of light sheet metal. The casing 1 is provided with spaced longitudinal skid members or supporting strips 2 on the bottom thereof while the top is provided with a central raised portion 3 having a width sufficient to interengage the adjacent side edges of the spaced skids 2 of a superimposed heater as shown diagrammatically in dotted lines in Figs. 1 and 2. One side of the casing is provided with a door or closure 4 which is hinged at 5 and provided with a suitable handle and latch 6 for holding the same closed. The front end 7 of the casing 1 is provided with a fresh air inlet port 8, preferably protected by a suitable screen mem-

ber 9. This inlet port has a large area so an appreciable volume of fresh air can be introduced or drawn therethrough into the interior of the cabinet 1 and is located in the upper portion of the cabinet. Extending inwardly from the port 8 toward the rear wall 10 is tubular fresh air inlet passage or duct 13 which is somewhat rectangular in cross section, although it may be cylindrical.

10 A second port of fairly large area is also located in the front wall 7 directly below the air inlet port 8 and constitutes a heated air outlet or discharge port 11 for discharging heated air from the interior of the cabinet in an appreciable volume, together with the products of combustion from a resonant pulse jet air circulating heater 22, later to be described. The outlet port 11 also receives an extensible flexible heat conducting tube 12 which is collapsible within the port, or extensible for connection to any suitable space to be heated, such as an engine nacelle, or other chamber, or a compartment of an aircraft or vehicle, for the purpose of delivering heated air to the space to be heated.

25 Referring now to Figs. 3 and 4, the rectangular fresh air inlet duct or conduit 13 extends inwardly from the front wall 7 and terminates in spaced relation to the rear wall 10. A double walled tube forming the heated air discharge 30 conduit is indicated generally at 15 and extends rearwardly within the casing from the outlet port 11 toward the rear wall 10 and comprises spaced inner and outer concentric cylinders 16 and 17, secured together at their inner ends at 19. The outer cylinder 17 is secured at one end to the front wall 7, around the periphery of the discharge port 11, and is supported at its other end by the standards 20, 21, the annular space 35 between the cylinders 16 and 17 thus provided, accommodates the flexible longitudinally extensible annularly corrugated tubular conduit 12, which is slidable into this annular space as shown, and collapsible between the cylinders 16 and 17 forming the inlet tube 15, or is extensible as desired.

40 The fresh air inlet and heated air discharge tubes 13 and 15 terminate within the casing 1 in spaced relation to each other in about the same vertical plane, intermediate the front and rear walls 7 and 10 as shown, so that fresh air entering and passing through the tube 13 must first pass into the relatively greater space of the interior of the cabinet before being introduced or drawn into the mouth or inner end of the hot air discharge tube 15. This arrangement produces a sound dampening or silencing effect in the space heater that will be explained later.

45 Located within the cabinet 1, at one side of the air intake and heat discharge conduits 13 and 15, is a resonant pulse jet air heating and air circulating structure or unit, the reference numeral 22 indicating this unit generally. The resonant pulse jet unit 22 comprises a combustion chamber 23 having an elongated discharge conduit or tail pipe 24 leading therefrom and acoustically tuned to a resonant frequency to produce rapid explosion impulses and oscillations when a suitable combustible fuel mixture is fed into the combustion chamber from below. The tail pipe 24 extends toward the rear wall 10 and is rebent on itself as at 25 and then extends forwardly, having an outwardly flared discharge outlet or nozzle 26 which projects materially into the inner end of the inner hot air discharge tube 50 or conduit 16, in concentric relation thereto,

substantially as shown in Figs. 3 and 4 of the drawings. The top or dome portion of the combustion chamber 23 is surrounded by a shroud member 27 which is uniformly spaced from the outer surface of the combustion chamber, the shroud member 27 having an air outlet port 28 in the side thereof through which the tail pipe 24 extends. An air heating and conducting tube 29 surrounds the tail pipe 25, and is connected at one end to the port 28 in the shroud 27, its other end being flared and terminating in an outlet port or mouth 30, concentrically surrounding the flared outlet end 26 of the tail pipe 24. Suitable supporting "spiders" 31 extend between the inner end of the heated air delivery tube 15 and the discharge end or mouth of the air conductor tube 29 and between the mouth 30 and the tail pipe 24, maintaining these tubes in spaced concentric alignment.

Located immediately in advance of the discharge outlet ports of the tail pipe 24 and the air conductor tube 29 is a Venturi nozzle 32 which tapers forwardly within the inner tube 16 and terminates at the front wall 7 of the casing 1. The combustion chamber 23, tail pipe 24, hood or shroud 27 and the air heating tube 29 being subject to extensive heat and vibrations, are therefore preferably constructed of stainless steel or other equally strong noncorrosive material. The combustion chamber 23 tapers downwardly from its head or dome portion and a check valve unit 33 is secured across the lower end of the combustion chamber as shown in more detail in Figs. 3 to 7.

We prefer to use free-floating or "flying" valves in the valve unit 33, as shown in Figs. 6 and 7, or resiliently actuated valves as disclosed in Figs. 8 and 9, in order to obtain a very rapid, completely free valve actuation.

The valve unit 33, as shown in Figs. 5 to 7 comprises an annular relatively heavy valve supporting plate 34 fastened at its periphery to the lower end portion of the combustion chamber, being formed with a multitude of closely spaced spherical depression or valve seats 36 each surrounding a combustible fuel mixture inlet port 37. The valves, denoted at 38, are very thin cup shaped disks each having a somewhat spherical curvature substantially conforming to the curvature of the seats 36.

Located immediately above the supporting plate 34, in spaced relation thereto, is an annular thin foraminous retainer plate or screen 39, formed with downwardly projecting substantially spherical protuberances 40 having contours which substantially fit the interiors of the cup shaped valves 38 when the valves are raised or floated upwardly by air and fuel entering through the ports 37 from a carburetor or fuel and air supply means located below, indicated generally at 41. When the valves 38 are seated on the plate 34 the ports 37 are closed. When valves are raised, air passes around the valves, through the perforations in the retainer plate 39 and into the combustion chamber 23.

A downwardly tapered fuel supply nozzle or tube, indicated at 42 in Fig. 5 is secured below the valve unit 33 and terminates in an outwardly flared Venturi inlet port 44 having a fresh air intake chamber 45. A central air and fuel mixing inlet tube 46 is suitably supported in the venturi 44 at 47. Concentrically located in the lower portion of the mixing tube 46 is a fuel jet 48 which is carried by a supporting spider 49, the fuel jet 48 being supplied with a suitable

liquid or gaseous fuel through the conduit 50 from a carburetor 51, being in turn supplied with a fuel, such as a liquid hydrocarbon, through the pipe 52 leading from a main fuel reservoir or tank 53 located within the cabinet 1 and supported by suitable standards 54, the tank 53 being provided with a filler opening and closure cap 55, accessible through the door 4.

The pulse jet unit is supported in any convenient manner, such as by suitable standards or brackets secured to the interior of the casing, or as shown, by a supporting bracket or strap 56 which is clamped around the exterior of the hot air outlet tube 15, as shown in Figs. 3 and 4, 15 with the ends thereof secured to the combustion chamber 23, at or near the check valve unit 33. The combustion chamber 23 may be provided with a jump spark plug 57 as indicated in Fig. 5 and associated suitable high tension current supply means 58 for supplying an electric spark to initially explode the combustion mixture within the combustion chamber to start the pulse jet cycle after a jet of compressed air under high velocity is directed into the fuel intake mixing tube 46 and past the fuel nozzle 48 to introduce a combustible fuel and air mixture through the check valves 38 and into the combustion chamber 23. We prefer however, to utilize an automatic, self-contained starting unit or set which 20 is indicated generally at 59. The use of this starting unit 59 eliminates the use of pumps, air pressure supply tanks, conduits, valves, etc., also eliminating the use of batteries, high tension coils, switches, spark plugs, etc., and provides other advantages later to be pointed out.

Once the pulse jet heater unit is set into operation there will be a vertically vibrating column of air and fuel within the intake nozzle 42 and the central fuel and air mixing intake tube 46 and in order to prevent "back pressure" at the fuel nozzle 48 as the check valves 38 close at the time of explosion within the combustion chambers 23, an upwardly tapered baffle member 60 is provided which is supported on a "spider" 61 directly above the nozzle 48, best seen in Fig. 5, 45 directing the downwardly moving column of the fuel mixture at this time outwardly away from the fuel inlet jet or jet 48.

The starting unit or set 59, as best seen in Fig. 5 comprises a combined fuel tank and pressure boiler 62 having a filler and deaerating opening and closure cap 63 and a drain passage and closure cap 64. Located directly below the boiler 62 is a suitably ventilated heating torch and wick compartment 65 having an asbestos wick 66 in the bottom thereof. A suitably valved fuel supply nozzle or tap 67 is preferably connected to the main fuel tank 53, or to the carburetor supply pipe 52 by a conduit 68 having a shut-off control valve 69 therein. A door 70 provides free access to the torch compartment for lighting the wick 66, suitable vents or apertures 71 being provided which supply the necessary air for the burning of the fuel in the heating wick compartment and for combustion in the heating retort tube 75.

Located concentrically within the wick compartment 65 is a fuel jet nozzle 72 having a needle valve 73 which is controlled by a hand wheel 74. Extending upwardly from a port in the bottom of the boiler 62 is a central upwardly flared venturi and retort heating tube 75 having its inlet end directly above and concentric to the fuel jet 72 and its outlet end at 76, above the top end closure of the boiler 62. Adjacent the

side of the boiler 62 and the wick and torch chamber 65 is a gasous fuel nozzle 77 having a fuel jet 78 and an elongated gaseous fuel pressure chamber 79, the chamber 79 being connected at its lower end by a conduit 80 to a chamber in the interior of the main fuel retort nozzle 12 and connected at its upper end by a fuel supply pipe 81 which passes through and is sealed in the wall of the boiler, extending upwardly therein and wrapped around the upper portion of the retort tube 75 within the boiler as indicated at 82, a gaseous fuel inlet port 83 being formed at its upper end just under the top end of the boiler 62.

The boiler 62 carries a laterally offset closed chamber 84 which surrounds the fuel jet 77. A gaseous fuel and air mixing tube 85 projects upwardly from a port in the top of the offset chamber 84 and is formed with a flared lower end 86 connecting the chamber, the upper end of the mixing tube 85 being in communication through a port at 87 with the interior of the combustion chamber 23. The tube 85 is welded or otherwise secured to periphery of the port just mentioned and forms a supporting arm for the starting unit 59.

The laterally offset chamber 84 is provided with a fresh air inlet port 88 in the top thereof which is controlled by a loose disk or flap valve 89, suitable guides therefor being provided. A vertical push rod 90 is slidable in a suitable guide passage 91 for the purpose of forcing the flap or disk valve 89 closed to prevent fresh air from entering the offset chamber 84.

The fuel nozzle 78 is controlled by a spring tensioned needle valve 92 slidable in a suitable guide passage formed in the lower portion of the nozzle structure below the elongated gaseous fuel chamber 79. A tubular extension 93 is formed on the lower end of the nozzle 78 having a spring seat at its lower end, housing a compression spring 94 which exerts valve closing thrust against a spring seat flange formed on the needle valve 92. The lower end of the needle valve 92 carries a bifurcated head 95 thereon which is formed with a vertical slot for receiving an actuating pin 96 that is fixed on an actuating lever 97. The lever 97 is pivoted at its inner end to a link 98, which in turn is pivoted to a bracket or ear 98' projecting from the heating torch wick compartment 65. The lever 97, as shown in Fig. 5, extends laterally beyond the lower end of the flap valve closing push rod 90 and is loosely connected to the push rod at 99 so that when the lever 97 is swung downwardly it will first lower the push rod 90 to release or free the flap or disk valve 89 and then continued downward movement will withdraw the needle valve 92. The extremity of the lever 97 carries a manual actuator or push button 100 for actuation thereof. A tension spring 101 is connected between the push rod guide 91 and the lever 97 for yieldably urging the lever upward to its closing position.

A pressure gage 102 is preferably provided which is connected to the interior of the boiler 62 by a suitable conduit 103, so as to determine the starting or fuel vapor pressure within the boiler 62. A safety valve 103' is connected to the conduit 103.

A heat and flame conducting and air mixing tube 104 is supported, as shown in the drawings, by a web 105, from the fuel introducing pipe 85, the tube being flared outwardly above the retort tube outlet 76 and also flared at its upper end with the upper end located closely adjacent to

the side of the pulse jet combustion chamber 23. The tube 104 inclines upwardly toward the combustion chamber so as to direct all of the heat from the starting unit against the side of the combustion chamber 23 to form a hot spot 106.

Operation

In starting the pulse jet heating unit the shut off valve 69 is first opened to saturate the wick 66 with fuel and is then closed. The door 10 is opened and the saturated wick is ignited in any convenient manner, such as by a match. Air entering the apertures 71 supports the combustion and the flame passes upwardly through the central heating retort tube 75, heating the same to cause some evaporation of fuel and a low pressure within the boiler 62. The heat also ascends the tube 104 and warms the pulse jet combustion chamber 23. After a short interval of time the hand wheel 74 is turned to open the needle valve 73 and nozzle jet 72 starting the retort. Fuel in the boiler is boiled, evaporated, and thus superheated by the coil 82. The gaseous fuel then passes down pipe 81, through the elongated chamber 79 and pipe 80 and through the fuel jet nozzle 72. Air is drawn through apertures 71 in the wick chamber 65 and the superheated gaseous fuel from the nozzle burns with intense heat which is directed upwardly through the tubes 75 and 104 against the side of the combustion chamber 23 heating the same to provide a very hot or igniting spot thereon as indicated diagrammatically at 106.

In the meantime, due to the intense heat passing through the boiler 62, pressure within the boiler will build up rapidly and the gage 102 should be noted to determine when a desired pulse jet starting pressure is reached, preferably in excess of 80 pounds. When the starting pressure is reached and the glowing spot is hot enough the push button 100 is depressed, releasing the flap valve 89 and withdrawing the needle valve 71, causing an explosive mixture of super heated fuel and air to be injected through the supporting conductor pipe 85 and into the combustion chamber 23 building up an explosive mixture therein under some pressure. This mixture finally reached the "hot spot" 106, which is still being heated by the starting set 59, and the mixture explodes, initiating the resonant pulse jet cycle. So long as the push button 100 remains depressed, fuel and air will be injected and sucked through the pipe 85 and into the combustion chamber, and when exploded the mixture column in pipe 85 will also explode, but the flap valve 89 will close, preventing escape of the combustion products through the port 88. When the push button 100 is released the needle valve 92 closes and the flap valve 89 is forced upwardly shutting off the air supply and starting fuel in the offset chamber 84 and the column of air in the pipe 85 becomes "dead" and only vibrates vertically in resonant frequency with the rapid explosions of the pulse jet cycle within the combustion chamber 23. The hand wheel 74 can now be turned to close the needle valve 73 and shut off the starting unit 59.

Referring now to Figs. 3 to 6 particularly, each explosion within the combustion chamber exhausts the heated gases therefrom through the tail pipe 24 at high velocity and they are discharged from the flared end 26 into the Venturi mouth 32. The jet of exhaust gases leaving the end 26 at high velocity creates a low pressure area 75 at the discharge end of the tail pipe which causes

a surrounding column of fresh air to pass into the hood or shroud 27, which surrounds the hottest portion of the combustion chamber, and move along the hottest portion of the exterior of the tail pipe 24, through the surrounding hot air pipe 29 in heat exchange relation, and be delivered at the end of the tail pipe into the Venturi nozzle 32 in surrounding relation to the column of hot combustion gases from the tail pipe. The rapid movement of these two columns of products of combustion and fresh heated air into the mouth of the air delivery tube 15, and through the aspirator mouth 32 causes a large quantity of fresh air, and any fuel or combustible vapors that may be present within the cabinet, to be withdrawn burned and discharged through the air delivery tube in a second surrounding column. This air being cooler than the inner two columns prevents the hottest portions of the columns from being on the outside, at least until after the heated air has been mixed with the cooler air and conducted materially through the flexible air delivery hose 12 toward the space to be heated.

Following each explosion or pulse the inertia of the rapidly expelled gases causes a reduction of pressure within the combustion chamber 23. This pressure reduction, as shown in Fig. 7, causes the free light weight or "flying valves" 38 to float upwardly against the screen 40 allowing the explosive mixture from below to enter from the valve ports 37 and pass through the screen or foraminous retainer plate 40 into the combustion chamber 23. The reduction of interior pressure in the combustion chamber now causes rapid return of a portion of the hot gases within the tail pipe, and the return inertia of these gases causes a rise in pressure within the combustion chamber which immediately forces the "flying valves" 38 closed, as shown in Fig. 6. The heat of the returned gases fires the new mixture causing the following explosion or pulse. The length and diameter of the tail pipe relative to the combustion chamber is important and determines the frequency in acoustic resonance to provide an extremely rapid pulse jet action which produces a continuous flow of a large volume of heated air through the heated air discharge pipe 15 and flexible conduit 12. The "flying valve" structure provides an extremely rapid resonant pulse jet action because the valves have very little weight and inertia and are always free to move, no springs being used for closing. Fresh air is, of course, allowed to flow freely into the cabinet 1 through the fresh air inlet tube 13 in great volumes to replenish the heated air that is withdrawn and discharged from the cabinet through the flexible conductor pipe 12. On the "suction" cycle, the fuel from the fuel jet 48 is induced to flow upwardly with an air column passing through the central air and fuel mixing intake tube 46 (Fig. 5) which passes around the deflector or baffle 60. The flow of air and fuel just described induces, through Venturi action, a surrounding flow of air, entering the chamber 45 from below, to flow into the tapered chamber 42 located below the valves 38. The fuel and air mixed therein is in the form of a vibrating column which moves upwardly and through the valve plate during the continued resonant pulse jet action continuing until the fuel supply valve 107 is closed. Back pressure in the rising vibrating column of the fuel and air mixture within the tube 46 is deflected away from the fuel jet nozzle 48 by the baffle 60.

In order to improve the "flying valve" action by resiliently actuating the free or flying valves, a novel and improved arrangement may be employed, as illustrated in Figs. 8 and 9. In this form cup shaped light weight valves 38^a are provided which are freely movable between a valve supporting plate 34^a, having fuel mixture inlet ports 37^a therein, and a spaced flat valve retainer plate or screen 39^a having the apertures 39^b therein in communication with the combustion chamber. A flat annular valve return spring 108 of disk shape is provided, having a resonant frequency substantially related to the desired pulse jet resonant frequency of the pulse jet unit one spring for each valve 38^a which is supported in spaced relation to the apertured retainer plate 39^a as shown.

The lower valve plate 34^a is provided with valve receiving depressions 36^a, covered by a thin apertured resilient plate 109 as shown, having a resonant frequency similar to the resonant frequency of the upper spring plates or disks 108. When the pulse jet unit is in operation at its tuned acoustic resonant frequency the spring plates 108 and 109 snap the valve cups 38^a to their closed and open positions in resonance, greatly accelerating the valve movement with a material increase in the efficiency of the pulse jet unit. Fig. 8 illustrates one of the cup shaped valves 38^a when moved toward closed position, with its lower spring actuator 109 under tension, while Fig. 9 illustrates one of the cup valves 38^a when moved upwardly toward fully open position, with the other spring actuator 108 placed under tension. The actuators 109 also cushion the return actuation of the valves 38^a against their seats during operation, reducing wear.

The extensible flexible heat conducting tube 12 is not necessarily subjected to excessive heat since the outer column of cooler fresh air within the cabinet 1 enters through the intake tube 9 and passes through the conduit 12 in surrounding relation to the hot gases from the combustion chamber 23 and from the heating shroud 27 and tube 29. The delivery tube 12 can thus be made of accordion pleated fabric, rubber (synthetic), plastic or other suitable material, and when in use the outer end will be disposed in communication with a space to be heated.

Referring to Fig. 10 a modified heating unit is disclosed in which a portion thereof is built into the engine nacelle which includes, if desired, a part of the pulse jet combustion chamber. The balance of the heating unit, including the remainder of the combustion chamber, starting unit, fuel tank, and other associated parts are built into a small compact cabinet, or inclosing casing or structure, which is easily and conveniently attachable to an aircraft engine nacelle when the aircraft or other vehicle is on the ground and not in operation. When attached and initiated into operation it will keep the power plant, oil tanks and other accessories at temperatures which are desirable for quick, easy and convenient starting, even under severe Arctic winter weather conditions.

In Fig. 10 an aircraft power plant nacelle is indicated at 110, the engine at 111, engine accessory group at 112, oil tanks, intercoolers etc. at 113 and 114. Venturi nozzles are located at 115 and 116, having heat conductor pipes 117, 118, 119 and 120 leading therefrom to surrounding shield or heat deflector means, for directing heat from the pipes just mentioned around the

parts to be maintained in the desired heated condition.

The reference numeral 1^a denotes an inclosing casing containing the major part of the resonant heating and starting units, fuel tank, etc. The fuel tank is denoted at 53^a having a filler opening and cap 55^a the tank supplying fuel to a carburetor 51^a. The combustion chamber of the pulse jet unit comprises an upper portion 23^a which is supplied with fuel and air at 42^a, similar to Fig. 5, supporting the starting unit 59^a, also similar to the starting unit 59 as disclosed in Fig. 5.

The upper portion of the combustion 23^a chamber however is split transversely and flanged, having suitable quick detachable securing means 121 therefor. The upper or dome portion of the combustion chamber is indicated at 122, having one or more acoustically tuned resonant tail pipes as indicated at 123 and 124 leading therefrom and are conveniently fixed within the nacelle 119, their discharge ends being located respectively in the inlet openings of the Venturi nozzles 115 and 116.

The resonant pulse jet heating unit 1^a is started in the same manner as the unit shown in Figs. 1 to 5. There are certain advantages however in this last described construction, especially in compact high speed planes. All hot and fresh air conduits can be conveniently and permanently located within the nacelle or engine compartment, and the tail pipes 123 and 124 which can be made of proper diameter and length to provide the desired acoustically tuned resonant frequency of the pulse jet unit and being welded to the dome portion 122 of the combustion chamber and opening externally of the compartment, no direct flame or fire can be introduced into the compartment and cause a fire hazard, also the tubing employed can be very light in weight and suitably strong.

The resonant pulse jet unit 1^a may be carried within the plane, or kept at the landing and servicing depots where it can be easily attached by the quick detachable connections 121 and initiated into operation. The fresh air which is induced at the Venturi nozzles 115 and 116 is heated by the hot gases leaving the flared outlet ends 123^a and 124^a of the tail pipes 123 and 124. This fresh air enters the nozzles 115 and 116 in surrounding relation to the hotter gases thus completely isolating the hot gases until a heat exchange and cooling of the hottest gases takes place. A secondary heating shroud and surrounding pipe for the combustion chamber and tail pipe, similar to the shroud 27 and pipe 29 in Fig. 3, may be provided, if desired to effect further heat exchange.

This form of resonant pulse jet heater concentrates the heat where it is most needed and no heat is wasted, also no fans or electrical apparatus are required for starting, circulating, and mixing the heated air.

It is to be noted that the heater arrangement as disclosed in Figures 1 to 5 provides an improved sound dampening or silencing action. Most of the noise of the pulse jet unit is caused by the vibrations of the air emanating from the flared nozzle or discharge port 26 of the tail pipe 24. The outlet tube 16 surrounds the end of the tail pipe 24 and overlaps or extends toward the closed end of the cabinet, materially beyond the discharge end. Also the heat delivery hose 12 which is connected to the space to be heated, and the concentrically surrounding flared discharge

nozzle 32 absorb and deaden most of the direct sound of the rapid explosions in front of the discharge pipe end 26. An appreciable amount of sound or vibrations are reflected rearwardly out 5 of the hot air discharge pipe 31 and into the interior of the cabinet structure 1. The location of the fresh air inlet duct 13 in spaced parallel relation to the hot air discharge tube 16, with both of their inner ends in communication with 10 a much larger space or area within the cabinet, between the ends of these tubes, permits the noise vibrations to be deflected around the interior of the cabinet and by the walls thereof which may be coated with a conventional sound deadening 15 covering, before the sound can be deflected out of the cabinet through the fresh air inlet duct 13. By this time most of the noise vibrations have been absorbed and reduced so that the noise of the pulse heater during its operation is not 20 great or objectionable.

If desired the intake tube 13 may be provided with a suitable "butterfly" valve as indicated at 25 125 which may be adjusted to regulate the amount of fresh air to be mixed at the Venturi 25 nozzle 32. This will effect the volume of heated air that is delivered, but will also affect the temperature of the air at the final delivery point. As the valve 125 is turned toward closed position 30 the temperature of the air delivered through the heated air delivery tube will be increased.

It will be obvious that various changes and modifications may be made in the apparatus as shown in the drawings, the same being submitted as an illustrative rather than a limiting sense 35 relative to the scope of the invention as defined in the following claim.

What we claim is:

In a resonant pulse jet air heating and circulating space heater, a substantially rectangular 40 enclosing casing having vertically spaced air inlet and heated air outlet openings in one end wall thereof; a resonant pulse jet heater fixed within the casing, comprising an elongated vertical dome shaped combustion chamber having 45 a fuel and air check valve controlled inlet port at its lower end in communication with the interior of the casing; means within the casing for supplying fuel and air to said inlet port to form a combustion mixture in the combustion chamber; said combustion chamber having an exhaust port in its side wall; a U-shaped tail pipe connected at one end to the exhaust port with its opposite end forming an exhaust end portion 55 facing the heated air outlet opening in spaced relation to the outlet opening; air heating conduit means surrounding the upper portion of the combustion chamber and tail pipe in spaced concentric relation thereto having an air inlet and surrounding the combustion chamber and a heated air outlet surrounding the exhaust end portion of the tail pipe; means within the casing 60 for heating the side of the combustion chamber opposite the exhaust port therein and below the air inlet of the air heating conduit means, for heating an area of the combustion chamber wall to a temperature sufficient to explode a fuel and air mixture when introduced into the combustion chamber, to initiate the resonant pulse jet cycle; manually controlled means within the casing 65 having a fuel and air mixture supply conduit connected in communication with the interior of the combustion chamber at a point below the area heated by the combustion chamber heating means and above the check valve controlled inlet port, including manually controlled valve means 70

governing the fuel and air mixture supply conduit and means under control of said manually controlled valve means for supplying heated fuel and air under pressure into the vertical heated fuel and air mixture conduit; Venturi means extending inwardly from the heated air outlet port of the casing having a flared mouth facing the exhaust end portion of the U-shaped tail pipe and heated air outlet of the air heating conduit means in surrounding concentric spaced relation thereto.
